UNITED STATES PATENT OFFICE.

OWEN MOYNIHAN, OF CLEVELAND, OHIO.

DESIGN FOR A PNEUMATIC-TIRE TREAD.

Application filed April 3, 1920. Serial No. 371,160. Term of patent 7 years

To all whom it may concern:

Be it known that I, OWEN MOYNIHAN, a citizen of the United States, residing at 3017 Essex Road, Cleveland, in the county of Cuyahoga and State of Ohio, have invented a new, original, and ornamental Design for a Pneumatic-Tire Tread, of which the following is a specification, reference being had to the accompanying drawing, forming part thereof.

In these drawings—

Fig. 1 is a plan view of a portion of the

tread of a tire casing, showing my new design.

Fig. 2 is a transverse section thereof.

Fig. 3, is a perspective of a portion, of the casing on which the tread is displayed.

Fig. 4, is a perspective of the complete casing or tire.

I claim—

The ornamental design for a pneumatic tire tread, as shown.

OWEN MOYNIHAN.
